UNITED STATES PATENT OFFICE.

MILTON FORDER, OF THIEF RIVER FALLS, MINNESOTA.

TIMER FOR AUTOMOBILES.

Application filed March 17, 1921. Serial No. 453,082.

To all whom it may concern:

Be it known that I, MILTON FORDER, a citizen of the United States, residing at Thief River Falls, in the county of Pennington and State of Minnesota, have invented a new and useful Timer for Automobiles, of which the following is a specification.

This invention has reference to timers for 10 automobiles and more particularly for the type of automobile known commercially as the "Ford" automobile.

The object of the invention is to provide a brush or movable contact rotatable with 15 the timer shaft and providing a more extended contact surface than is possible with the customary roller contact, and one which provides more reliable engagement, thus materially reducing resistance at the contact 20 and thereby causing the passage of larger current and obtaining at the spark plugs a more intense or "fatter" spark than before.

In accordance with the invention, there is provided a casing with a circular series of 25 contacts from which the current is distributed to the spark plugs in the usual manner, the invention being confined to the movable contact or brush engaging the fixed contacts of the timer. The brush comprises a 30 helix of wire fitting snugly on the end of the timer shaft within the timer casing and the helix is made fast to the timer shaft with one end of the helix in trailing relation to the timer shaft, expanding therefrom and 35 approaching the contacts embedded, as is customary, in a ring track within the casing. The outer or free end of the trailing contact or brush is formed in a manner to bear upon the inner face of the track carrying the contacts, and also upon one side face thereof, thus giving an extended contact surface for 40 the passage of the current.

The invention will be best understood 45 from a consideration of the following detailed description taken in connection with the accompanying drawing forming part of this specification, with the understanding, however, that the invention is not confined to any strict conformity with the showing in 50 the drawing, but may be changed and modified so long as such changes and modifications mark no material departure from the

salient features of the invention as expressed in the appended claims.

In the drawing:—

Fig. 1 is a rear face view of an automobile timer constructed in accordance with the invention.

Fig. 2 is a perspective view of a timer brush or wiper of the type shown in Fig. 1. 60

Fig. 3 is a face view of a terminal contact on the brush of the form shown in Figs. 1 and 2.

Fig. 4 is a view similar to Fig. 1, but provided with a brush or wiper comprising one 65 piece of metal.

Fig. 5 is a perspective view of the brush or wiper in Fig. 4.

Referring to the drawings, there is shown a timer cover 1 with an internal annular track 2 of insulating material in which is partially embedded a circular series of contact plates 3 equidistantly spaced about the axis of the cover 1 and each connected to a binding post 4, exposed on the exterior of the cover for 70 the attachment of conductors 5 and leading to the induction coil units of the ignition system, which latter is not shown.

The cover 1 is entered by a timer shaft 6 and on the shaft there is mounted a brush 7 designed to participate in rotary movements of the timer shaft and to wipe over the contact plates 3 in wiping engagement therewith.

The brush 7 is formed with a helical coil 8, shown separately in Fig. 2, such coil being formed of wire, preferably of round cross section. The helix 8 is a more or less closed helix and terminates at one end in a loop 9 through which there is passed a pin 10 arranged transversely of the shaft 6 so that the coil 8 is constrained to rotate with the shaft. The other end of the helix 8 is prolonged into a bend 11 extended first lengthwise of the helix for a distance, and then bent into a curved arm 12 generally radial to the axis of the helix, and then in trailing relation thereto, as shown at 13.

The terminal coiled portion 14 of the arm 12 is wrapped about a tongue 15 formed on a contact block or plate 16 as a continuation of the tongue 15, the coiled portion 14 being tightly wound about the tongue 15 and extended through the perforation 17 of the

block 16 or more than one such perforation. The block 16 is of plate-like conformation with an extended edge 18 having a nose 19 projecting from one end of the edge 18 in substantially right angular relation thereto having both the edge 18 and tongue 10 where rising from the edge 18 suitably rounded, as shown at 20, so as to ride along the track 2 and over the faces of the plates or contacts 3 with the rounded edge of the tongue 19 bearing against one side face of the track and making contact with the exposed side edges of the contacts 3. This affords both face and edge engagement between the contact plate 16 of the brush and the contact plates 3 of the track 2.

The helix 8, because of its shape, will elastically yield to pressure of the contact block 16 upon the timer track 2 and against the contact plates 3, and this yielding effect is participated in by the curved arm 12 so that as the shaft 6 is rotated, the edges 20 of the block 16 bear elastically upon the timer cover with such pressure as the elastic force generated by the rotation of the block 16 which the timer shaft will cause.

A similar effect is produced by the brush structure shown in Figs. 4 and 5, the structure of Figs. 1 and 4 with respect to the brush being similar except that the arm 13 terminates in a return loop 16^a arranged to bear flat against the track 2 with the free end of the return loop 16^a bent into a tongue 19^a serving the same purpose. The brush in the structure of Figs. 4 and 5 designated by the reference numeral 16^a is elastically pressed against the contact plates 3 with the tongue 19^a bearing against the side of the track 2 and engaging the edges of the contact plates 3.

The collecting brush 16 is to be preferred to the return loop 16^a, which is made in one piece with the coil 8 and the arm 13, because it has greater wearing qualities and is more sturdy.

The advantages possessed by the structure of Fig. 1 overbalance the disadvantage of the two-piece structure of Fig. 1, in that there is less liability of breaking than occurs with the all-wire form of Fig. 4.

What is claimed is:—

1. In an automobile timer structure, a rotatable contact brush comprising a wire helix for attachment to the timer shaft to rotate therewith and having a wire arm in trailing relation to the helix in the direc-

tion of rotation and provided at the free end with a contact positioned to wipe over stationary timer contacts.

2. In an automobile timer structure, a circular series of substantially stationary contacts and a rotatable contact for successively engaging the stationary contacts and comprising a helix adapted to the timer shaft for rotation therewith and terminating in a contact or brush yieldingly connected to one end of the helix and at the other end in trailing relation to the helix.

3. In an automobile timer structure, a rotatable contact brush comprising a wire helix for attachment to the timer shaft to rotate therewith, and having its end bent and extended lengthwise of the helix, then bent into a curved arm substantially radial to the axis of the helix, and then bent in trailing relation to the helix in the direction of rotation, and provided at the free end with a contact positioned to wipe over stationary timer contacts.

4. In an automobile timer structure, a rotatable contact brush comprising a wire helix for attachment to the timer shaft to rotate therewith, and having a wire arm in trailing relation to the helix in the direction of rotation, said arm being provided at its free end with a coil extending radially inward, and a contact block seated and held within the coil on the free end of the arm, said contact member being adapted to wipe over stationary timer contacts.

5. In an automobile timer structure, a circular series of substantially stationary contacts and a rotatable contact for successively engaging the stationary contacts and comprising a helix adapted to the timer shaft for rotation therewith and terminating in a contact yieldingly connected to one end of the helix and at the other end in trailing relation to the helix, said rotatable contact consisting of a block having an extended edge and a nose projecting from one end at an angle thereto to engage both the inner face and one side edge of each of the relatively stationary contacts, said rotatable contact being separately formed from the helix and connected to and movable therewith.

In testimony that I claim the foregoing as my own, I have hereto affixed my signature.

MILTON FORDER.
